(57) **CLAIM**

We claim the ornamental design for a stand-up paddle board with a viewing window, as shown and described.

DESCRIPTION

FIG. 1 is a top perspective view of a stand-up paddle board with a viewing window.

FIG. 2 is a bottom perspective view of the stand-up paddle board with a viewing window of FIG. 1.

FIG. 3 is a top plan view of the stand-up paddle board with a viewing window of FIG. 1.

FIG. 4 is a bottom plan view of the stand-up paddle board with a viewing window of FIG. 1.

FIG. 5 is a right side elevation view of the stand-up paddle board with a viewing window of FIG. 1.

FIG. 6 is a left side elevation view of the stand-up paddle board with a viewing window of FIG. 1.

FIG. 7 is a front elevation view of the stand-up paddle board with a viewing window of FIG. 1.

FIG. 8 is a rear elevation view of the stand-up paddle board with a viewing window of FIG. 1; and,

FIG. 9 is an enlarged cross-sectional view of the stand-up paddle board with a viewing window of FIG. 1 taken along line 9-9 of FIG. 5.

The broken lines illustrate portions of the stand-up paddle board with a viewing window that form no part of the claimed design.
